SNOW MELTING MACHINE

Sanford I. Wadsworth, Jackson Heights, N. Y.

Application April 14, 1955, Serial No. 501,313

2 Claims. (Cl. 126—343.5)

This invention relates to a snow melting vehicle or machine.

It is an object of the invention to provide a snow melting vehicle having a blower to deliver finely divided snow into a chamber where it will be melted by the hot, burning gases within the chamber and drained from the chamber as water.

It is another object of the invention to provide a snow melting vehicle in which the hot exhaust gases used to melt snow blown into a melting chamber are recirculated through the chamber by a gas turbine device which delivers intense heat.

It is still another object of the invention to provide a snow melting vehicle operated by a gas turbine engine which delivers and propels hot exhaust gases to melt finely divided snow at the point the gases are blown into the chamber and in such a manner as to effect injection or Venturi action into the delivered snow.

It is still another object of the invention to provide a snow melting vehicle in which a portion of the hot exhaust gases used to melt finely diffused snow in the chamber are exhausted with the melted snow and directed toward the ground surface.

It is a further object of the invention to provide a snow melting vehicle having means for distributing salt to the melted snow or water as it is discharged from the melting chamber to prevent later freezing on the ground surface.

It is a still further object of the invention to provide a snow melting vehicle having an angled scraper to divert the discharged heated water toward the gutter.

It is a still further object of the invention to provide a snow melting vehicle in which snow picked up by a rotary pick up and delivery device is fed to a high-speed blower which finely diffuses the snow and delivers it into a melting chamber.

Other objects of the invention are to provide a snow melting vehicle having the above objects in view which is of simple construction, inexpensive to manufacture and operate, is compact, has a minimum number of parts, does a complete snow removal job, is efficient and economical in operation and easy to use.

For other objects and a better understanding of the invention, reference may be had to the following detailed description taken in connection with the accompanying drawing, in which:

Figure 1 is a side elevational view of the snow melting vehicle with parts broken away to show more clearly certain details;

Fig. 2 is a top plan view of the snow melting vehicle shown in Fig. 1;

Fig. 3 is a sectional view of the vehicle taken on line 3—3 of Fig. 1;

Fig. 4 is a front view of the snow melting vehicle, showing the scoop, viewed from the line 4—4 of Fig. 2;

Fig. 5 is an elevational view of a snow throwing chute removed from the snow delivery duct.

My improved snow removing vehicle generally includes

2

a truck having a chassis, motor and operator's cab; a rotary snow pick up and delivery unit is mounted in front of the truck and the snow melting unit is mounted on the truck chassis behind the cab.

5 I am aware that there are a number of prior art snow melting machines. However, the prior art does not show a compact snow melting device of large capacity which can be operated at low cost. My device melts snow rapidly in a relatively small unit because finely divided snow is blown into the exhaust blast from a gas turbine of the aircraft type.

Referring now to the drawings, 10 represents a motor truck and chassis having an offset operator's cab 11 and an offset internal combustion engine 12. Since the truck is of conventional construction, it will not be described in detail. Other types of vehicles or carriers can be used.

A conventional snow rotary pick up and delivery unit 13 is mounted on the front of truck 10. The unit 13 includes a frame 14 which supports shafts 15, 16 and 17. A plurality of rotary blades 18 are mounted on shaft 15 and are longitudinally and angularly spaced from one another. Spaced blades 19 are mounted on shaft 16. The latter shaft is driven through differential 20 by drive shaft 21 which takes power from pancake or flat shaped combustion engine 21'. Shaft 16 drives shaft 15 through idler shaft 17 by means of sprockets 22, 23 and chain 24, and sprockets 25, 26 and chain 27. The sprockets are dimensioned to have blades 19 rotating at 30 a much higher speed than blades 18. The ratio of speed of the blades 19 to the blades 18 is six to one.

Rotating blades 18 cut up the packed snow 28 and throw it up over contoured surface 29 to rapidly rotating blades 19. The latter blades further break down the 35 snow and blow it at high speed through duct 30 into melting chamber unit 31. Since the rotary pick up and delivery is conventional, it need not be described in full detail. The duct 30 is split to provide branch pipes 30' and 30" for respectively receiving the snow from the 40 respective spaced sets of blades 19, Fig. 2. The duct 30' has a removable plate 32 secured to the upper surface thereof and upon being removed a snow diverting duct 72, Fig. 5, can be inserted to deliver snow to the side of the truck at times when the melting chamber unit 31 is 45 not needed.

The melting chamber unit 31 is supported upon the truck 10 in rear of the cab 11. This chamber unit is made of a high temperature resisting steel alloy and an inner cylindrical-shaped-wall 31' of the chamber is coated 50 with ceramic or other fireproof material. The duct 30 is flared as indicated at 30a at the location where it extends into the chamber 31. The snow is accordingly delivered from the flared end 30a in such a manner as to spread snow through the chamber and direct it toward 55 circular burner units 33 and 34.

Each burner unit has a circular manifold 35 with radially-inwardly extending burner nozzles 36 to direct flames into the center of the chamber toward which the blast of snow entering the melting chamber is directed 60 from the flared entering end of the snow delivery duct 30. Fuel is supplied to the burners from a fuel tank 37 mounted upon the top of the melting chamber unit 31 at the rear end thereof, through a pipe line 38, a fuel pump 39, a fuel supply line 40 leading from the pump and branch pipes 41 and 42 respectively connected with the 65 burner units 33 and 34. An electric motor or other power means 43 drives the pump 39. A magneto 44 supplies electric ignition current through cable 45 and branch cables 46 and 47 that respectively connect with respective spark terminals 48 of the respective burner units 33 and 34. Ground terminal elements 49 are provided on the 70 burner units adjacent to the respective terminals 48 to

draw the igniting sparks across the fuel supply nozzles 36.

The chamber unit has a downwardly and rearwardly inclined bottom 51 over which the water resulting from the melting of the snow drains and into a drop chamber passage 52 and onto the road surface for flow off to the side of the road. On the drop chamber passage is a scraper device 53 having an inclined scraper blade 54 for collecting and directing the movement of the water toward the side of the road. In order to prevent the water from freezing and to leave the road surface without glare ice, a salt supply box 55 is mounted on the chamber and has a drain pipe 56 that directs the salt to the road surface behind the scraper blade 54.

In order to heat the chamber adjacent to the bottom 51, the exhaust gases from the pancake engine 21' that drives the snow pick-up and delivery device on the front of the truck and from the truck engine 12 are directed by ducts 57 and 58 leading respectively therefrom and entering the chamber 31 at one side thereof to direct the exhaust gases over the lower portion of the chamber.

A gasoline supply tank 59 is mounted on the chamber unit 31 forwardly of the fuel tank 37 for supplying gasoline to the truck engine 12 through the pipe 60 and to the snow pickup and delivery device pancake engine 21' through pipe line 61.

To provide further means to recirculate the heated gases in the chamber a recirculating duct 62 is mounted on the top of the melting snow chamber and has an inlet connection 63 from the top of the rear portion of the melting chamber 31 and a flared outward end 64 surrounding or concentric with the flared end 30a of the snow duct 30 to effect injection action upon the snow entering the melting chamber from the duct 30.

A damper gate 65 is hinged at 66 and is adjusted by means of a hand wheel mechanism 67 located forwardly adjacent to the cab 11 on general control panel 67' therein to position the damper between the inlet connection 63 and an external air supply opening 67a to control the mixture of gases and air delivered to the duct 62 to a gas turbine engine 68 of the aircraft type having mounting brackets 69 and 70 that secure the turbine within the duct 62 and upon the top of the melting chamber 31. Fuel is supplied to this gas turbine from the fuel tank 37 by a pipe 71. Accordingly, not only will the gases be re-burned when being circulated through the duct but further gases and propelling action will be maintained so that the chamber will be constantly supplied with moving hot gases to insure full treatment of the snow and to prevent any stoppage or piling up of such snow in the melting chamber. The gas turbine may be used alone under some conditions to melt the snow in the chamber.

In Fig. 5, there is shown snow chute 72 that is inserted into the snow duct 30 upon removal of the plate 32 at times when only a minor snow operation is needed of the machine and when the snow is not deep on the ground. The snow melting chamber and equipment is dispensed

with at this time. This chute 72 has an angularly adjustable upper end as indicated at 72' to direct the snow to the side of the vehicle. Its lower end has a deflector 73 that will lie within the duct 30 to direct the snow upwardly from the duct 30 as it is blasted therethrough. A longitudinally-extending fire wall 75 is mounted on the top of the snow melting chamber 31 to isolate the gas turbine 68 from the fuel and gasoline tanks 37 and 59, Fig. 3.

10 It should now be apparent that there has been provided a snow melting vehicle means for picking up snow and delivering it under pressure to a melting chamber where there is provided an adequate amount of heat to instantly and efficiently convert the snow to water so that it may be drained or led off from the road surface.

15 It will be seen that any one of the sources of the hot gases may be effected and can be used independently or together as the case may demand to melt the snow.

20 It is also apparent that the heating arrangements can be built into a stationary machine or upon portable household carriages.

25 While various changes may be made in the detail construction, it shall be understood that such changes shall be within the spirit and scope of the present invention as defined by the appended claims.

What is claimed is:

1. A snow melting machine comprising a melting chamber having a snow inlet duct in one side thereof, a gas recirculating duct connected between another side of the 30 melting chamber and the one side thereof, said duct at its connection with the one side of the chamber surrounding and concentric with said snow inlet duct to produce a suction effect upon the snow entering the chamber through the snow inlet duct and to diffuse the snow entering the melting chamber, and a fuel and air consuming gas turbine engine in said recirculating duct to reheat, re-burn and supply hot snow melting gases to the melting chamber.

2. A snow melting machine as defined in claim 1 and 40 a fuel burner mounted in the melting chamber to direct flame upon the snow entering the chamber and valve means in the recirculating duct between the melting chamber and the turbine engine to permit control of the amount of gases leaving the melting chamber there- 45 through.
